UNITED STATES PATENT OFFICE.

WALTER THOMPSON, OF BROOKLYN, NEW YORK.

MEANS FOR PREVENTING THE JAMMING OF MACHINE-GUNS.

1,371,527.

Specification of Letters Patent. Patented Mar. 15, 1921.

Application filed August 12, 1918. Serial No. 249,397.

To all whom it may concern:

Be it known that I, WALTER THOMPSON, subject of the King of Great Britain, residing at Brooklyn, in the county of Kings and 5 State of New York, have invented new and useful Improvements in Means for Preventing the Jamming of Machine-Guns, of which the following is a specification.

My invention relates more particularly to 10 means for preventing the jamming of machine guns.

One of the difficulties in the successful operations of automatic or semi-automatic guns such, for instance, as machine guns, is 15 that due to the jamming of the gun mechanism, rendering the gun useless until the jammed condition is overcome.

I have discovered that one of the main causes of this difficulty is the tendency of 20 the percussion cap to be displaced from its seat thus disturbing the operating conditions in such manner as to prevent the normal functioning of the operating mechanism.

25 This displacement may take place in any one of a number of stages and lead to jamming. For instance, it may occur in feeding and affect the feeding operation or prevent proper firing and thus prevent proper 30 operation of the ejecting mechanism. But the principal cause of such difficulty is due to the effect of the firing of the cartridge, the expansion of gases tending to displace the cap from its seat in the cartridge base, 35 thus affecting the operating mechanism and producing the jam, as by changing the general configuration of the base to vary it from that required for co-operation with the firing and ejecting mechanisms, or by 40 forcing the cap away from the seat and into the operating mechanism thereby jamming the latter.

This displacement of the cap is made possible by the difficulty presented in initially 45 positioning the percussion cap, this positioning being had, mainly by automatic machinery and subject to possible imperfections, together with the difficulties of inspection to determine the certainty of 50 proper anchorage of the cap.

The present invention is designed to meet this problem by positively anchoring the cap against displacement, and a preferred way is to upset the material of the cartridge base 55 into an anchoring formation relative to the

positioned cap. This may be provided in advance of the location of the cartridge in the feeding mechanism of the gun—as, for instance, at the time of cartridge manufacture—or this anchoring formation may be 60 provided within the gun mechanism—as, for instance, concurrently with the striking of the cap so that the anchor is formed to withstand the effects of the gas expansion.

In either case, the cartridge shell has its 65 percussion cap anchored against displacement relative to its seat, this anchorage being present when the cartridge has been fired, and may be present in advance of the firing in case the anchorage is formed prior 70 to locating the cartridge in the gun.

To these and other ends, the nature of which will be readily understood as the invention is hereinafter disclosed, said invention consists in the improved construction 75 and arrangement of parts hereinafter fully described, illustrated in the accompanying drawings, and more particularly pointed out in the appended claims.

In the accompanying drawings, in which 80 similar reference characters indicate similar parts in each of the views:

Figure 1 is a view partly in section and partly in elevation of portions of a firing mechanism of a standard machine gun construction.

Fig. 2 is a view partly in section and partly in elevation of the firing mechanism.

Fig. 3 is an enlarged detail view of a portion of the firing pin, showing one way in 90 which the anchorage may be provided, parts being broken away for clearness.

Fig. 4 is a perspective view of a cartridge shell showing the percussion cap anchored in position.

The present invention is designed more particularly to meet a condition and difficulty which may occur in the operation of machine guns, as heretofore pointed out, although the general invention is not limited 100 to such use.

The solution of the problem which is provided by the present invention consists in anchoring the percussion cap against displacement from its seat in the cartridge 105 base, this being preferably provided by upsetting the metal of the base into an anchorage formation relative to the cap. This is shown in Fig. 4 in which 10 indicates the cartridge base, generally of metal and 11 in- 110

dicating the percussion cap positioned in the base, the latter carrying the seat for the cap. As shown in this view, the metal of the base adjacent to the perimeter of the 5 cap has been upset, as at 12, so as to carry this upset portion over into the path of travel which would be taken by the cap when displaced to shift it from its seat. This upsetting action may be provided in 10 any way as by a punch-like action on the metal of the base at a point spaced from the base opening into which the cap extends, thus displacing the metal of the base in a direction to extend over the cap.

15 As heretofore pointed out, this anchoring formation may be provided at the time when the cartridge or cartridge base is being manufactured, or it may be provided subsequent thereto, since the upsetting operation 20 is of a character which does not tend to fire the cap. When produced during the manufacture, the cartridge carries the displacement-preventing means in advance of use, with the means so formed as to not affect the ability of the cartridge to be used 25 in any desired fire arm.

The invention however is not limited to the production of this anchor formation in advance of positioning in the fire arm, since 30 the formation may be provided during firing operations. For instance, in Figs. 1 to 3 I have shown parts of a standard machine gun, the firing pin 13 of which carries one or more elements or devices 14 which serve 35 to produce this upsetting action at the time when the pin is operating in connection with the percussion cap. The device 14 is shown as in the form of an upsetting element which is brought into contact with the base of the 40 cartridge by the movement of the firing pin and at a point in proximity to the base opening within which the cap is seated, Fig. 3 showing the general action of the device at this time.

45 No detail description of the particular gun mechanism shown is given since the invention is applicable to different types of machine guns, and may, if desired, be utilized in connection with the ordinary rifle 50 or gun or any of the automatic or semi-automatic guns in general use, these all operating with firing pins of different types.

It will be understood, therefore, that the 55 general invention is not limited to the particular time of production of the anchor formation nor the particular mechanism which may be employed in producing it, since, as above pointed out, it may be produced at the time of cartridge manufacture 60 by mechanism other than the mechanism of the gun, or it may be produced at the time of cartridge use and by mechanism carried by and forming a part of the gun mechanism. Nor is the invention limited to its use in

connection with machine gun operations, although its preventive action becomes most efficient in connection with use under automatic or semi-automatic conditions where jamming of the gun becomes a critical difficulty. 65

70 While I have herein shown and described preferred ways in which the invention may be carried out, it will be readily understood that changes and modifications therein may be found essential or desirable in meeting 75 the individual conditions of use, and I desire to be understood as reserving the right to make any and all such changes or modifications as may be found desirable or essential, in so far as the same may fall within the 80 spirit and scope of the invention as expressed in the accompanying claims when broadly construed.

What I claim is:

1. In a gun adapted to fire a cartridge 85 provided with a percussion cap, means for holding the cartridge in firing position including a breech block and means movable relative to the breech block operative during firing upon the cartridge shell to prevent 90 displacement of the percussion cap.

2. In a gun adapted to fire a cartridge provided with a percussion cap, means for holding the cartridge in firing position including a breech block and means movable 95 relative to the breech block operative during firing to force a portion of the cartridge base into position behind the percussion cap to anchor said cap in place.

3. In automatic or semi-automatic gun 100 operation wherein the cartridge is fired by a firing pin, means for preventing jamming of the gun by anchoring the percussion cap to its seat in the cartridge base, said means comprising a device movable with said pin 105 and operative to upset metal of the base into an anchoring formation relative to the cap.

4. In a gun adapted to fire a cartridge provided with a percussion cap, means for holding the cartridge in firing position including a breech block and means movable 110 relative to the breech block operative during firing for striking up a portion of the cartridge shell adjacent the percussion cap to form an anchor adapted to maintain said 115 cap in position in the shell.

5. In a gun adapted to fire a cartridge provided with a percussion cap, a breech block, a firing pin and means shiftable relative to said breech block into engagement 120 with said cartridge shell base simultaneously with the impact of the firing pin on the percussion cap to force said base into engagement with the cap to retain it in position in the base. 125

6. In combination, machine gun firing mechanism including a firing pin adapted to fire a positioned cartridge by striking the

cartridge percussion cap, and means movable with said pin and operative on the cartridge base to upset metal of the latter into an anchoring formation relative to the percussion cap.

7. In a gun adapted to fire a cartridge provided with a percussion cap, a firing pin and means connected to the firing pin adapted to force the base of said cartridge into

engagement with the cap to retain it in position in the base.

8. In a gun adapted to fire a cartridge provided with a percussion cap, a firing pin and means rigidly connected to and moving with the firing pin, adapted to force the base of said cartridge into engagement with the cap to retain it in position in the base.

WALTER THOMPSON.
